No. 892,170.

PATENTED JUNE 30, 1908.

J. B. MAHONEY.
CARD INDEX DEVICE.
APPLICATION FILED JAN. 24, 1908.

UNITED STATES PATENT OFFICE.

JOHN B. MAHONEY, OF UTICA, NEW YORK.

CARD-INDEX DEVICE.

No. 892,170.

Specification of Letters Patent.

Patented June 30, 1908.

Application filed January 24, 1908. Serial No. 412,397.

To all whom it may concern:

Be it known that I, JOHN B. MAHONEY, of Utica, in the county of Oneida and State of New York, have invented certain new and useful Improvements in Card-Index Devices; and I do hereby declare that the following is a full, clear, and exact description thereof, which will enable others skilled in the art to which it appertains to make and use the same, reference being had to the accompanying drawings, and to the letters of reference marked thereon, which form part of this specification.

The object of my invention is to provide an improved index card holding device for use with desk telephones more particularly, and which device is simple in construction and convenient and efficient in use.

Figure 1 shows a perspective view of a desk telephone with my improved card holding device mounted thereon. Fig. 2 shows a section taken on line 2, 2 of Fig. 1 on an enlarged scale, and with the cover plate and index cards in partially open position. Fig. 3 is a similar section taken on line 3, 3 of Fig. 1, showing the device closed. Fig. 4 is a plan view of the back plate and attached parts out of which the body of the device is constructed. Fig. 5 is a plan view of the movable plate or cover. Fig. 6 shows one of the index cards. Fig. 7 shows the hinge pin, and Fig. 8 shows a spring employed in the construction.

Referring to the reference numbers and characters in a more particular description, 35 10 indicates the back plate, which is provided on one side with an integral ear or projection 10^a having a relatively large hole or opening adapted to receive the secured end of the 40 telephone mouthpiece 11. These mouthpieces are ordinarily screw-threaded on their attaching ends and engage in the front wall of the diaphragm chamber 12 of the telephone. By removing the mouthpiece the 45 index device can be placed, and by replacing the mouthpiece with the screw-threaded end passing through the opening in the ear 10^a, the device may be readily secured to the telephone in a convenient position for use.

50 Formed integral with the back plate 10 is a bottom plate 14 made to assume a right angular position with reference to the back plate by a bend. In addition there is formed integral with the bottom part 14 the card 55 retaining guideways 15, which, as to a por-

tion of their length, are curved as shown, and they may be connected to the back plate by being provided with ears 15^a passing through openings 16 and clenched on the rear side. A top flange 17 is provided on the part 10, 60 which, being given a right angular position to the body, provides a protection for the upper edge of the index cards. Side retaining ears 18, 18 may be also provided.

The movable plate or cover 19 is provided with a projection 19^a, having a cylindrical eye which receives the spring 20, the pintle 21 passing through the spring when located in the eye. The part 14 is cut out, as indicated at 22, to receive the cylindrical eye of the part 19, and the pintle 21 is held to the underside of the part 14 by keepers 23 provided by slitting the material and deflecting the intermediate strip of material between the slits, so as to provide eyes to receive the 75 ends of the pintle 21. The arms on the opposite ends of the spring 20 are arranged to engage with the movable plate 19 and the stationary part 10, and the spring is tensioned to throw the movable plate or cover 19 into 80 closed position. The card retaining slideways 15 are spaced somewhat apart and are adapted to receive the ear or tab 25^a of the index cards 25 between them, and the tabs 25 are undercut at each side to engage and 85 run on the inner edges of the slideways 15. A set of several cards 25 may be employed in the holder, and these will preferably be cut away at different points and severally indexed, as shown in Fig. 1.

When attached to a telephone, as shown in Fig. 1, the device will be in a more or less upright position with the hinge and card retaining guideways at the bottom. It is evident that ready access may be had to any one 90 of the several cards of the set by turning down more or less the cover or movable plate 19 and with it such number of cards as may be necessary to expose the desired card. The substantially straight portion of the guideways 15 is practically equal to the thickness of the total number of cards of the set, while the curved portions of the guideways are substantially concentric with the hinge. This being so a considerable number of cards can 95 be turned down in conjunction with the cover or movable plate without binding and with ease and facility. When the cover and such cards as may be swung outwardly in connection with it are released, the spring 110

20 will operate to return the cards to the pack, and the cover to its closed position, holding them properly in the pack. When the cover or movable plate 19 is in its full 5 open position, the cards may be removed or replaced singly by turning them at an angle to the plane which they normally occupy. This angular position will free the hook portions of the ear or tab 25^a from the edges of 10 the retaining slideways 15. The slideways 15 being relatively wide on their face afford a substantial base for the edges of the cards to rest on, which is quite material in view of the fact that the cards would be ordinarily of 15 paper stock and the guides 15, together with the bottom 4, provide quite a complete housing for the ears or tabs 25^a and give the article an appearance which is not objectionable.

20 The idea of securing the index device to the telephone by utilizing the ordinary fastenings for the mouthpiece is considered quite important, in that the size of the mouthpiece is substantially standard in all the various makes of telephones and enables the 25 index device to be attached to any telephone without modification or inconvenience. Further than this, the mouthpiece with its diaphragm chamber is ordinarily hinged to the stand and by mounting the index device, as 30 shown, the angular adjustment of the mouthpiece also angularly adjusts the position of the index device. The cards will ordinarily be employed as an abbreviated list of telephones 35 subscribers, the names and telephone numbers being entered on the cards substantially as shown in Fig. 6, although it is evident it is adapted for other uses.

It is evident that modifications and changes 40 in and from the construction described may be made without departing from the spirit of my invention or the subject matter so long as they are within the scope of the claims.

What I claim as new and desire to secure by Letters Patent is:

45

1. The combination in a card index of a back plate having a pair of spaced card retaining guideways secured at one end to the back and extending therefrom first in a straight and then in a curved plane, a movable spring closing plate hinged to the back at a point concentric with the curved portion of the guideways, and cards having notched edges fitting upon said guideways and interposed between the said plates, substantially as set forth.

50

2. The combination in a card index of a back plate, the bottom part arranged at right angles with the back plate, a pair of spaced card retaining guideways secured at one end to the back and extending therefrom first in a straight and then in a curved plane to the outer edge of the bottom, a movable spring closing plate hinged to the bottom at a point substantially concentric with the curved portion of the guideways, and cards having notched edges fitting upon said guideways and interposed between said plates, substantially as set forth.

55

3. A card index device consisting of a back plate having an ear projecting substantially in the plane of the back plate and having an enlarged opening whereby it is adapted to be attached to a telephone transmitter as set forth, a movable plate hinged at the lower end to the back plate, a spring operating to close the movable plate against the back plate, and a set of cards mounted on the back plate, substantially as set forth.

60

In witness whereof, I have affixed my signature, in presence of two witnesses, this 20th day of Jan. 1908.

JOHN B. MAHONEY.

Witnesses:

SARAH E. CLARK,
GEO. E. RENDELL.
